UNITED STATES PATENT OFFICE

GLENN F. COUCH, OF ROCHESTER, NEW YORK, ASSIGNOR TO THE SYMINGTON COMPANY, OF NEW YORK, N. Y., A CORPORATION OF MARYLAND

JOURNAL BOX

Application filed May 12, 1926. Serial No. 108,511.

The present application is a continuation in part of my now abandoned, originally co-pending, application Serial No. 18,997, filed March 28, 1925 on journal boxes.

5 This invention relates to journal boxes for railway cars, and more particularly to the construction of spring-actuated journal box lids.

10 The principal object of the invention, generally considered, is the provision of what may be designated as an articulated lid construction pivoted to the journal box by means of a hinge pin which may be held in place by special locking tabs or be only 15 adapted for insertion or removal when the members comprising the articulated lid are positioned in given angular relation with respect to each other, which relation is other than the normal operative relation between 20 said members.

25 An object of my invention is the provision of a journal box lid with a spring retainer articulated with respect thereto, said lid and retainer being pivoted to the journal box and with respect to each other by means of a self-locking pin which is only adapted for longitudinal movement into or out of normal position when said spring retainer and lid occupy a given angular relation with respect 30 to each other.

35 Another object of my invention is the provision of an articulated journal box lid comprising a lid proper, a spring retainer, a spring held therebetween for locking or holding said members in normal operative relation, and a hinge pin or pintle for pivotally connecting said members, said pintle being provided with a portion so formed that longitudinal movement thereof is prevented 40 when the lid and retainer are positioned in normal operative relation, but permitted when one of said members is rotated a predetermined amount with respect to the other.

45 A further object of my invention is the provision of an articulated journal box lid including a spring retainer which normally holds a spring in energized position with respect to said lid, whereby said spring serves to hold said lid in either open or closed position and lock said retainer in normal position

with respect to said lid, a self-locking pintle connecting said lid and spring retainer, whereby said members are normally held in rotative relation and loss or removal of said pintle is prevented except when the retainer 55 is moved from normal operative relation with respect to the lid so that withdrawal of the pintle is permitted.

A still further object of my invention is the provision of an articulated journal box 60 lid consisting of a closure member, a spring retainer, and a spring held in energized position therebetween and serving to lock said members in normal operative relation with respect to each other, and a pintle or hinge 65 pin for pivotally connecting said members, a portion of said pin being non-circular or of flattened formation so that pivotal motion with respect to the spring retainer is prevented, one of the dimensions of the flattened 70 portion being greater than one of the dimensions of the hinge loops on the lid whereby insertion or withdrawal of the pin is prevented except when the retainer occupies a given angular relation with respect to the 75 lid.

80 Other objects and advantages, pertaining to the various elements and combinations thereof, will become apparent as the description proceeds.

In the drawings illustrating my invention, the scope whereof is defined by the claims:

Figure 1 is a front elevational view, partly in section, of a portion of the lid, showing the parts in assembled relation.

Figure 2 is a cross-sectional view on the line 2-2 of Figure 1, looking in the direction of the arrows.

Figure 3 is a side elevational view of a portion of the lid and spring retainer when said spring retainer is positioned for insertion or withdrawal of the hinge pin.

Figure 4 is a side elevational view of a portion of the lid and spring retainer when in normal operative relation with respect to 95 each other.

Figure 5 is a cross-sectional view on the line 5-5 of Figure 1, looking in the direction of the arrows.

Figure 6 is a front elevational view of a 100

modified form of lid and spring retainer therefor.

Figure 7 is a cross-sectional view on the line 7—7 of Figure 6, looking in the direction of the arrows.

Figure 8 is a front elevational view of another modified form of lid and spring retainer therefor.

Figure 9 is a cross-sectional view on the line 9—9 of Figure 8, looking in the direction of the arrows.

Referring first to the construction illustrated in Figures 1 to 5, inclusive, a journal box, designated by the reference character 1, is illustrated provided on its upper surface 2 and adjacent the forward edge thereof, with a hinge lug 3, which is perforated at 4 for the passage of a hinge bolt or pintle 5 therethrough.

20 The journal box is preferably of standard A. R. A. construction and the lug thereon is provided at its front and top with flat faces 6 and 7, respectively, for cooperation with a spring-pressed portion carried by the lid 8 for holding the same in either closed or open position. The lid 8 is advantageously formed of pressed metal and provided with hinge loops or ears 9 and 10 surrounding the ends of the hinge pin 5, whereby the same is maintained in pivotal relation with respect to the journal box 1.

25 A spring retainer 11, formed with cooperating ear or loop portions 12 and 13, also surrounding the pintle 5 for pivotally connecting the retainer with the journal box and also with the lid 8, is provided. Between the retainer 11 and the lid 8 is positioned a spring 14 which is held by said retainer in energized position, whereby said 30 spring is adapted for resiliently holding the lid in either open or closed position. As illustrated, said spring preferably comprises a plurality of coiled portions 15 and 16, joined by a relatively straight portion 17 upon 35 which, in the embodiment shown, is mounted a roller 18 which engages the hinge lug 3 and alternately presses against the faces 6 and 7 thereof when the lid is in closed and open positions, respectively.

40 The ends of the spring 14 may extend downwardly and be bent toward each other at 19 and 20, where they are retained in pivotal relation with respect to the lid 8 by means of a clamping device 21, preferably 45 securely fastened to the lid by means of a rivet 22. When the spring member is free, as when the retainer is moved away from the lid 8, the roller 18 does not function to hold the lid in the desired relation with respect to 50 the journal box. When, however, the spring retainer 11 is moved to the position shown in Figure 2, the curved surface or surfaces 23 thereon engage the coils 15 and 16 of the spring and move the same to normal operative position, where said spring is locked in

position in the pocket or pockets 24 in the retainer 11.

For the more convenient actuation of the spring retainer 11, the same is provided with a relatively long operating arm 25 which extends well beyond the clamping device 21 on the lid 8 so as to provide a relatively large leverage for operating the spring retainer by hand to or from the position shown in Figure 2. The operating lever or arm 25 is preferably perforated at 26 and 27, for lightening the weight thereof and providing apertures in which an operating bar may be inserted, if desired, for more conveniently moving the spring retainer to energize or deenergize the spring 14.

20 The pintle or hinge pin 5 is so constructed that it is what may be designated as self-locking. That is, it may only be positioned or removed when the spring retainer 11 occupies a given angular relation with respect to the lid 8, which angular relation is that illustrated in Figure 3. The hinge pin or pintle, for this purpose, is formed with a flattened or non-circular portion 28 thereon, which portion registers with the loop 12 on the spring retainer, which is, of course, of corresponding formation.

25 From a consideration of Figure 3 particularly, it will be apparent that the loop portion 12 on the spring retainer 11 is formed with an elongated aperture 29 therein, which extends substantially longitudinally with respect to said retainer so that the pintle 5 is adapted for insertion therein when the elongated or non-circular portion 28 thereof extends longitudinally with respect to the spring retainer 11. The loop 9 on the lid 8, on the contrary, is formed with an elongated or non-circular aperture 30 which extends transversely with respect to said lid. Both of the apertures 29 and 30 are formed of substantially the same length as the elongated portion 28 on the hinge pin and of a width less than the length of said elongated portion 28, and corresponding substantially to the normal diameter of the pin, so that said pin 5 may only be inserted or moved longitudinally with respect to both the loops 9 and 12 when the spring retainer 11 is arranged substantially at right angles with respect to the lid 8 or in such a position that the elongated apertures 29 and 30 are arranged to substantially coincide, as shown in Figure 3.

30 The aperture 4 through the hinge lug 3 is preferably circular and adapted for receiving the circular portion of the hinge pin 5 and preventing the non-circular or elongated portion 28 thereof from passing therethrough. The loop 13 on the retainer is formed in substantially the same way and the loop 10 on the lid may be correspondingly formed although it is preferably formed elongated, as shown in Figure 4, corresponding with the loop 9

shown in Figure 3, but merely for the purpose of allowing enough play to permit the lid 8 to seat properly with respect to the journal box 1.

On account of the aforescribed construction, the hinge pin 5 can only be inserted in position and removed from position when the retainer 11 and lid 8 occupy substantially the relative positions illustrated in Figure 3, in which the sectional axes of the aperture 29 and 30 through the loop portions 12 and 9, respectively, are substantially parallel with other.

After insertion of the hinge pin 5, the spring retainer 11 is preferably moved to the position shown in Figure 2, when it is resiliently locked in place with respect to the lid 8, by engagement of the spring 14 in the pocket or pockets 24 of the retainer. When such is effected, the hinge pin 5 is locked in position and no auxiliary locking device or cotter is necessary for preventing loss or undesired removal of said hinge pin, because it cannot move to the left on account of the length of the non-circular portion 28 being greater than the width of the non-circular aperture 30, and it cannot move to the right because the length of said portion 28 is greater than the diameter of the aperture 4 30, in the hinge lug 3.

Another desirable feature accomplished by the present construction of pintle or hinge pin, is that, because of the cooperation between the elongated portion 28, on said pin, and the aperture 29 through the loop portion 12 on the retainer, rotation between said members is prevented and said pintle therefore always occupies the same relative position with respect to said retainer and, when 40 in operative relation, the same relative position with respect to the lid also.

The side edges of the lid 8 are preferably formed with downwardly extending flanges 31 and 32. The lower edge of said lid is advantageously provided with a lip portion 33 for conveniently opening and closing the same. If formed of pressed metal, the lid 8 is preferably corrugated or embossed, as shown, for rigidifying the same.

The upper portion of the spring retainer 11 is preferably rearwardly extended, as shown in Figure 2, forming a flanged or hooded portion 34 which overlies the roller member 18 in the upper edge of the lid 8 for excluding foreign matter from the journal box. The rearward edge of this flange 34 is preferably reinforced by means of a rib 35 which also serves for draining water from the flange 34.

When assembled, as shown in Figures 1 and 2, the construction of the various parts is such that an operator may open the lid by grasping either the lip 33 or the spring retainer 11 at the end of the operating arm 25 thereof, because the force required to move

the spring retainer with respect to the lid is greater than that required to move the lid with respect to the journal box.

In Figures 6 and 7, a modification of my invention is illustrated, in which a lid 8^a is shown pivotally connected with respect to a journal box 1 by means of a hinge pin 5 which is of similar construction to that disclosed in connection with Figures 1 to 5, inclusive. The spring retainer 11^a, however, although 70 pivotally connected with respect to the journal box 8^a in a manner similar to that heretofore described, is of somewhat different construction. It is provided with a flange or hook 36 which is retained or held by means 75 of a latch member 21^a, which is preferably pivotally connected with respect to the lid 8^a by means of a rivet 22^a.

The spring 14^a, in this modification, is formed as heretofore, with a plurality of 80 coiled portions 15^a and 16^a, which may be of larger diameter, as illustrated. A relatively straight portion 17^a connects said coiled portions 15^a and 16^a, but instead of being provided with a roller, as in the previous modification, is formed with a wear plate 18^a which engages with the faces 6 and 7 on the hinge lug 3 in a manner similar to that described in connection with the first 90 modification.

The ends of the spring are preferably only continued downwardly a short distance where they are held in pockets 37 and 38 in the spring retainer 11^a, rather than as heretofore being clamped to the lid. When in 100 operative position, the spring 14^a is held between pocket 24^a on the spring retainer and extends into the pocket 39 on the lid 8^a.

In stressing or energizing the spring 14^a in the present modification, it is advantageous to position said spring in proper relation with respect to the retainer 11^a when said retainer is angularly disposed with respect to the lid 8^a. Said spring retainer, after positioning the spring so as to be held in the 110 pocket 24^a and the securing pockets 37 and 38, is then rotated about the pintle 5 to the position illustrated in Figure 7, where it is locked in place with respect to the lid 8^a by moving the latch 21^a from the position shown in dot and dash lines, to that illustrated in full lines in Figure 6. Although this operation of stressing the spring to lock the retainer and spring in position, may be effected by manually pressing the lower portion 115 of the spring retainer, yet, if desired, a lever or bar may be inserted in the aperture 26^a and serve for the more convenient stressing of the spring. An upper aperture 27^a may also be provided in the spring retainer for lightening the weight thereof.

The hinge pin or pintle 5 is inserted and locked in place in the same manner as described in connection with the first modification. That is, it is necessary that the 120

spring retainer and lid occupy an angular relation with respect to each other, as illustrated in Figure 3, in which position the pin is freely movable longitudinally to or from position.

When positioned, the retainer may then be moved to overlie the lid, as shown in Figure 7, and held in place by the spring 14^a, and also locked in place by means of the latch

21^a. When the retainer and lid occupy such relative positions, the hinge pin is held locked in place by the elongated portion 28 thereon, as described in connection with the first modification.

Except as specifically described in connection with Figures 6 and 7, the modification there illustrated, is substantially the same as that illustrated in Figures 1 to 5, inclusive, a hood portion 34^a of corresponding construction, being also provided as in the first modification.

In Figures 8 and 9, a modification of my invention is illustrated in which the hinge pin or pintle 5^b is formed as a straight cylindrical pin of uniform diameter rather than by being constructed of the self-locking type as shown in the previous embodiments. The advantage of this construction is a cheapening of the pin 5^b but, as such a pin is not self-locking, it must be retained in place by some auxiliary means as, for example, locking tabs 40 and 41 provided on the hinging ears or loops 9^b and 10^b, respectively, of the lid. Preferably one of the tabs, 40 for example, is normally in locking position as shown in Figure 8 and the other tab 41 is in extended or open position so that the plain pin 5^b may be inserted in place to hingedly connect the hinge lug 3, the lid 8^b, by passing through the hinging ears or loops 9^b and 10^b, and the spring retainer 11^b by passing through corresponding hinging portions 12^b and 13^b thereon, and locked in place by bending the tab 41 over the aperture in the ear 10^b or to a position corresponding with that of the tab 40, as shown in Figure 8. It is to be understood that such tabs may also be used on lids constructed in accordance with Figures 1 to 7, inclusive. As in the previous modifications, the lid is preferably formed of pressed metal although the corrugations or embossments thereon may be of slightly different configuration, as illustrated.

The spring retainer 11^b is preferably formed quite similar to that illustrated in Figures 1 to 5, inclusive, but, of course, the apertures through the ear or loop portions 12^b and 13^b need not be elongated but are merely of an appropriate size for fitting the cylindrical pin 5^b. The hinge loops or ears 9^b and 10^b may be formed with apertures therethrough just big enough to fit the pin 5^b but said apertures are preferably elongated, as shown in Figure 9, corresponding with the construction of the loop 10 shown in Fig-

ure 4, merely for the purpose of allowing play to permit the lid 8^b to seat properly on the face of the journal box 1. The spring 14^b preferably corresponds substantially with the spring 14 of the first embodiment and is preferably provided with an anti-friction roller 18^b which engages the hinge lug 3 in a manner similar to that described in connection with the first embodiment.

The ends of the spring 14^b may be retained in pivotal relation with respect to the lid 8^b by means of a clamping device 21^b which is preferably securely fastened to the lid by means of rivets 22^b and holds the ends 19^b and 20^b of the spring 14^b in a corrugated or grooved portion 42 formed in the face of the lid 8^b.

As in the first described embodiment of my invention, the spring is gradually energized, after pivotal connection to the face of the lid by means of the clamping device 21^b, by moving the spring retainer 11^b from a position projecting from or angularly disposed with respect to the lid 8^b to the position illustrated in Figure 9 during which movement the coils 15^b and 16^b of the spring 14^b are engaged by the curved or cam shaped surface or surfaces 23^b thereby gradually tensioning or stressing the spring until the coils 15^b and 16^b engage and lock in the pocket or pockets 24^b in the retainer 11^b. Except as specifically described and illustrated, the modification shown in Figures 8 and 9 may be substantially identical with the modification shown in Figures 1 to 5, inclusive.

By virtue of the foregoing construction, it will be apparent that a spring-actuated articulated lid has been provided which is readily operated by hand for energizing and de-energizing the spring and which has means thereon for efficiently excluding dirt and other foreign matter from the journal box. The pintle or hinge pin is either plain or self-locking so that it may only be moved into or out of position when the spring retainer and lid occupy angular or relative positions other than normal.

Another desirable feature is that, because of the engagement between the non-circular portion on the pintle and the cooperating loop on the retainer, said pintle and retainer, as well as the lid, when the parts are arranged in normal operative relation, are all retained and prevented from angular motion therebetween so that undesired wear is prevented.

The spring pressure tending to force the lid toward the journal box is exerted substantially centrally and, provision being made for allowing angling between said spring and lid, a tight engagement will be effected between all edges of the lid and journal box.

Having now described my invention, I claim:

1. In combination, a journal box having

5 a hinge lug, a lid provided with loop portions, a spring retainer provided with a plurality of loop portions registering with the loop portions of the lid, one of said loop portions being substantially circular and the other non-circular in section, with a dimension larger than the diameter of the circular loop portion, and a pintle of generally circular section corresponding to that of the loop portions, connecting said box, lid and retainer, provided with a non-circular portion corresponding to that of the non-circular loop on the retainer, the lid loop portion adjacent the non-circular retainer loop portion being 10 non-circular with its short dimension normally disposed substantially in the axial plane of the long dimension of the non-circular retainer loop and smaller than said long dimension, whereby said pintle is adapted 15 for longitudinal movement with respect to the lid loop portions when the retainer is moved from normal cooperating engagement with respect to the lid, and prevented from such movement, or locked in position, when 20 said retainer and lid occupy normal relative positions.

2. In combination, a journal box having a hinge lug with a cylindrical aperture, a lid with hinge loops, a spring retainer with cooperating loops, a hinge pin, of a diameter corresponding generally to that of said lug aperture, extending through the lug, lid and retainer loops for pivotally connecting said members, one of the loops on the retainer, 30 that portion of the pin normally received therein, and the adjacent lid loop being larger in one transverse dimension than the lug aperture diameter, the large dimension of the lid loop being normally disposed at 35 an angle to the large dimension of the retainer loop, and the short dimension of said lid loop being smaller than the large transverse dimension of the pin so that longitudinal movement of the pin through the lid 40 loop or lug aperture is prevented when the lid and pin are disposed in normal operative relation, but such movement through the lid loop is permitted when one of said members is rotated a predetermined amount with respect to the other.

3. In combination, a journal box having an apertured hinge lug, a lid provided with hinge loops, a spring retainer with cooperating hinge loops, a spring adapted for actuating said lid and holding the same in open or closed position, said spring being normally disposed between said retainer and lid and serving to hold said retainer in normal position with respect to said lid, a pintle extending through the journal box lug, and loops on the lid and retainer for pivotally connecting said members, one of the loops on the retainer, a portion of the pintle received therein, and the adjacent lid retainer loop 55 being extended laterally, the extension of

the pintle and retainer loop being normally transverse to the extension of the adjacent lid loop, and the long dimension of the extended portion of said pintle being greater than the short transverse dimension of the adjacent lid loop, whereby longitudinal movement of said pintle with respect to said lid loop is normally prevented until a predetermined amount of rotation occurs between said retainer and lid.

4. In combination, a journal box having an apertured hinge lug, a lid with hinge loops, a spring retainer with co-operating loops, a spring disposed between said retainer and lid and serving to hold said members in normal operative position, a hinge pin normally circular in section extending through the journal box lug and the loops on the lid and retainer for pivotally connecting said members, one of the loops on the retainer and the normally enclosed portion of the pin being extended laterally beyond the normal surface of said pin so that pivotal motion therebetween is normally prevented, the adjacent lid loop having a corresponding lateral extension normally disposed at an angle to the extension on the pin so that said pin will then be held from longitudinal movement therethrough, such longitudinal movement being permitted only when said retainer and pin are disposed in a predetermined abnormal angular relation with respect to said lid when the lateral extension on the pin registers with that of the lid loop.

5. In combination, a journal box having an apertured hinge lug, a lid with retainer loops, a spring retainer with cooperating loops, a hinge pin extending through the journal box lug and the loops on the lid and retainer for pivotally connecting said members, one of said retainer loops and that part of the pin therein being laterally extended so that rotation therebetween is prevented, the adjacent lid loop having a corresponding extension normally disposed at an angle to the pin and retainer extension so that passage of the pin through said loop is prevented when the parts are in normal position, but permitted when said pin and lid loop are disposed in abnormal angular relationship.

In testimony whereof I affix my signature.
GLENN F. COUCH.
